CLAIM

The ornamental design for an editing control panel, as shown and described.

DESCRIPTION

FIG. 1 is a perspective view of an editing control panel showing our new design, the broken-line showing of the surrounding elements being for illustrative purposes only and forming no part of the claimed design;

FIG. 2 is a top plan view thereof;

FIG. 3 is a front elevational view thereof;

FIG. 4 is a left side elevational view thereof;

FIG. 5 is a right side elevational view thereof; and,

FIG. 6 is a rear elevational view thereof.
